UNITED STATES PATENT OFFICE.

VICTOR HAYES KELLEY, OF MADISON, WISCONSIN, ASSIGNOR TO MADISON TOOL AND STAMPING WORKS, OF MADISON, WISCONSIN.

GAUGE FOR MORTISING MACHINES.

Application filed May 21, 1926. Serial No. 110,788.

This invention relates to gauges for mortising machines and for other machines of this type.

Objects of this invention are to provide a combination hold down and top back gauge, commonly known as top back fence to hold the upper portion of the work down and to hold the rear face of the work true with reference to a vertical line, so that the upper back gauge may be accurately aligned with the lower back gauge, and thus the mortise may be cut true from its top to its bottom, irrespective of the height or width of the work.

In actual practice with mortising machines it has been found difficult to cut the mortise in a wide piece of work. Usually the ordinary types of mortising machines are provided with a table with a back gauge which holds the work correctly at its lower portion, but which does not insure the accuracy of the top portion of the work. Obviously, therefore, an operator has considerable difficulty in properly cutting the mortises in a true and accurate manner.

This invention overcomes the defects noted, and provides a simple and easily adapted device which may be quickly applied to standard machines, and which is so constructed that it does not interfere with the free operation of the machine but which insures the utmost accuracy and permits the rapid forming of mortises, even in relatively wide and ordinarily, difficultly handled work.

An embodiment of the invention is shown in the accompanying drawings in which:—

Figure 1 is a front view of a mortising machine showing the device in position.

Figure 2 is a side view of the structure shown in Figure 1.

Figure 3 is an enlarged plan view of the attachment, such view being taken approximately on the line 3—3 of Figure 1, the parts of the mortising machine being merely indicated in such view.

Referring to the drawings, it will be seen that a standard type of mortising machine has been illustrated with guides or ways 1, and with a bottom table 2, provided with a rear gauge or back stop, commonly known as a back fence, and indicated by the reference character 3.

The mortising machine may employ any of the usual mortising tools; for example,

the box chisel, as indicated at 4, such chisel being operated from a motor 5.

The device comprises a body portion 6 which, in reality, is a plate overhanging the work 7. This plate slides upon the ways 1, and is provided with guides 8 which hold it in place. It may be locked in position in any suitable manner, as by means of a set screw 9, as most clearly shown in Figure 3. The body portion 6 is provided with a pair of parallel slots 10 through which clamping bolts 11 pass. Preferably the adjacent faces or marginal portions of these slots are formed of finished bosses 12, so that the screw heads or washers carried by the bolts 10 may have a perfect fit. Below the body portion or hold down a back stop or back fence 13 is positioned and receives the lower ends of the clamping bolts 11. Thus the back stop may be adjusted with reference to the body portion 6 to accommodate any thickness of work. Preferably, the body portion 6 is provided with a cutout 14 through its front edge to accommodate the mortising tool.

In using the device, for instance, to cut a mortise in a relatively wide door or panel, as indicated by the reference character 7, it is merely necessary to adjust the device to the correct height and to properly adjust the back stop or back fence 13, so that it aligns with the lower back stop 3. Thereafter, it is merely necessary for the operator to rest the work upon the table 2 and hold it against the back stop. This insures a perfect alignment of the mortise with the work so that the utmost accuracy may be attained. Obviously, the operator may interchange the work rapidly and thus the machine may be used at its utmost capacity with assurance that accurately and correctly aligned mortises will be formed.

It will be seen that a very simple and cheaply produced device has been provided by this invention, which may be very quickly applied to standard types of mortising and similar machines, and which may be adjusted to accommodate any height or thickness of work.

It will be seen further that this device will insure the utmost accuracy of the mortise and will permit the rapid manipulation of the work.

It is to be understood that in the event that extremely wide work has to be mortised

that the bottom table may be removed and suitable supports may be placed upon the floor for the reception of the work.

Thus it will be seen that the device may 5 accommodate a wide variety of work, and insure the desired accuracy.

Although the invention has been described in considerable detail, such description is intended as illustrative rather than limiting 10 as the invention may be variously embodied and as the scope of such invention is to be determined as claimed.

I claim:

1. An attachment for a machine having 15 guides and having an operating tool, said attachment comprising a body portion adapted to overhang the work and having a back stop mounted on its lower side, a pair of slides carried by said body portion and 20 slidably engaging the guides, and means for locking said slides in position.

2. A combined hold down and top back fence comprising a body portion having a guide receiving slides, and having a trans- 25 verse back fence adjustably mounted upon its lower side.

3. In a mortising machine the combina- 30 tion of a mortising tool, mechanism for driving said tool, vertical guides, a bottom sup- port carried by said guides and having a

back stop, a holding down device adapted for positioning above said work and having slides for engaging said guides, said holding down device having means for locking it in position upon said guides, a transverse 35 back stop mounted below said holding down device and adapted to engage the rear face of the work, and means for adjustably locking said transverse back stop with reference to said holding down device. 40

4. In a mortising machine the combination of a pair of vertical guides, a mortising tool mounted adjacent said guides, mechanism for operating said tool, a holding down device slidably carried by said guides, means 45 for locking said device to said guides, said device having a body portion projecting outwardly from said guides and adapted to overhang the work, said body portion having a cutout to permit the passage of the 50 mortising tool, and having a pair of parallel slots, a transverse bar forming a back stop and mounted below said body portion, and a pair of clamping bolts passing through said slots and adjustably locking said bar to said 55 body portion.

In testimony that I claim the foregoing I have hereunto set my hand at Madison, in the county of Dane and State of Wisconsin.

VICTOR HAYES KELLEY.
